UNITED STATES PATENT OFFICE.

EDWARD HEMSTRAM, OF GREATFALLS, MONTANA.

VEGETABLE GRATER AND MASHER.

SPECIFICATION forming part of Letters Patent No. 731,362, dated June 16, 1903.

Application filed January 15, 1903. Serial No. 139,186. (No model.)

To all whom it may concern:

Be it known that I, EDWARD HEMSTRAM, a citizen of the United States, residing at Greatfalls, in the county of Cascade and State of Montana, have invented certain new and useful Improvements in Vegetable Graters and Mashers; and I do declare the following to be a full, clear, and exact description of the invention, such as will enable others skilled in the art to which it appertains to make and use the same.

This invention relates to vegetable cutters, graters, and mashers, and particularly to screw-fed machines of this class.

15 The object of the invention is to provide a machine of this character which shall be simple of construction, durable in use, comparatively inexpensive of production, efficient in operation, easily cleansed, and one in which provision is made for scraping the feeder and preventing packing of the material in the hopper.

With this and other objects in view the invention consists of certain novel features of construction, combination, and arrangement of parts, as will be hereinafter more fully described and particularly pointed out in the appended claims.

In the accompanying drawings, Figure 1 is 30 a side elevation of my improved vegetable grater. Fig. 2 is a longitudinal section of the same, showing in full and broken lines the operation of the scraper. Fig. 3 is a vertical cross-sectional view. Fig. 4 is a detail view 35 of the scraper detached.

Referring now more particularly to the drawings, the numeral 1 represents the barrel or cylinder of the machine, in which is located a spiral screw-compressor 2, fixed to a 40 shaft 3, which is journaled at its rear end in a bearing 4, formed in a removable cap 5, having bayonet-slot connections 6 with the rear end of said barrel or cylinder. The cap 5 thus closes the rear end of the cylinder. The 45 forward end of the shaft has a journal 7, which turns in a bearing 8 in a cap or grater-head 9, having one or more bayonet-slot connections 10 with the forward end of said cylinder and forming a closure for the said end 50 of the cylinder and a grating member coöperating with the spiral compressor. The

outer end of the journal 7 is screw-threaded to receive a nut 11, by means of which the shaft 3 and the compressor are held in position and adapted to turn or rotate without 55 backward or forward movement in the cylinder, as hereinafter described. By removing the nut 11 and cap 5 the compressor may be withdrawn from the barrel or cylinder, so as to allow the parts to be thoroughly cleaned. 60 A crank 12 is applied to the rear end of the shaft 3, whereby the same may be rotated to cause the screw to feed the vegetable or other substances to be mashed or grated toward the head 9.

65 The forward portion of the barrel 1 is provided with longitudinal ribs 13, which form surfaces against which the edges of the forward convolutions of the feed-screw 2 are adapted to impinge and constitute wear-surfaces, by means of which a close connection is afforded between the screw and forward portion of the cylinder, the said ribs giving the necessary grip to the screw to secure a positive feed at the point where the material 70 is being forced through the head 9. The head 9 is formed, as shown, with openings for the outlet of the material. The cylinder is provided with an ordinary form of flaring hopper 14, in which the material is placed 75 and through which it is fed to the interior of the cylinder.

An essential feature of my invention consists in the provision of a scraper for preventing the material under treatment from sticking to the forward convolutions of the feed-screw or compressor, and thus preventing 80 said material from crowding or packing at the forward end of the machine. This scraper consists of a blade 15, extended in a direction 85 lengthwise of the machine and connected to a head 16, adapted to slide against the inner surface of the wall of the cylinder. From this head extends a screw-threaded shank 17, which projects upward and outward through 90 a longitudinal slot formed in the upper portion of the wall of the cylinder and passes through a reciprocating guide-bar 18, having dovetailed edges sliding in a dovetailed 95 guideway 19, formed on the exterior of the cylinder. A clamping-nut 20 is applied to the shank 17 and draws the head 16 up against 100

the inner surface of the cylinder and clamps the guide-bar 18 with a desired force or friction against the walls of the guideway 19. The guide-bar 18 is provided with a lug or projection 21, against the forward side of which bears the free end of a plate or ribbon spring 22, fixed at its opposite end to the front wall of the hopper 14. This spring exerts its energy against the forward movement 5 of the guide-bar and scraper and serves to return the same to their normal positions.

In operation the vegetables to be grated, mashed, or otherwise treated are placed in the hopper and the crank rotated. The spiral 15 compressor engaging said vegetables will force them downwardly and forwardly into contact with the head 9, which head, according to its construction, will grate or otherwise act upon the vegetables and discharge them 20 at the forward end of the cylinder or barrel 1. The normal position of the parts is shown in Fig. 2, from which it will be seen that the scraper 15 normally bears against the front side of the second spirally-curved portion or 25 convolution *a* of the compressor 2 in rear of the head 9. When said compressor is rotated to the right, the scraper 15 removes the material sticking to the front surface of said convolution *a* and is then forced by the spring 30 22 rearwardly through a slot *b*, formed in said convolution. As the compressor continues to rotate the scraper remains inactive between the convolution *a* and the spirally-bent portion or convolution *c* of the 35 compressor in rear thereof until the rear portion *d* of the spiral member *a* is again brought into contact with the scraper through the revolution of the compressor, when the edge of the scraper contacts with said portion *d* 40 and removes the material therefrom. This action is continued until the scraper again reaches the slot *b*, when it is again projected rearwardly of the portion *a* by the spring 22. It will of course be understood that in 45 the operation of the parts as just described the forwardly projected or advancing portion *d* of the compressor will exert pressure on the scraper 15 and force the same forward, the shank 17 sliding in the slot of the barrel 50 to accommodate this movement against the tension of the spring 22, until, as before stated, the scraper-blade again comes into register with the slot *b*, when the spring will react and force the scraper rearwardly, thus 55 projecting it through the slot *b* in the manner previously described. By this means the

front portion of the scraper will be kept clear of the adhering vegetables or substances and the latter prevented from packing at the forward end of the cylinder or barrel 1. The 60 scraper-blade is provided with a hard-metal wear-piece 15', against which the compressor bears, to prevent the edge of the blade from being dulled from hard rubbing contact with said compressor. 65

From the foregoing description, taken in connection with the accompanying drawings, the construction and operation of the invention will be readily understood without requiring a more extended explanation. 70

Various changes in the form, proportion, and the minor details of construction may be resorted to without departing from the principle or sacrificing any of the advantages of this invention. 75

Having thus fully described my invention, what I claim as new, and desire to secure by Letters Patent, is—

1. In a machine of the character described, the combination with a barrel, and a spiral 80 compressor operating therein, one of the convolutions of said compressor being formed with a slot, of a scraper movable longitudinally within the barrel and contacting with the compressor and adapted to move forwardly under the action of the same, and conforming to the surface of a portion of said compressor, and a connection between the scraper and barrel, yielding to the forward motion of the scraper and adapted to project 85 it backward through the slot, substantially as described.

2. In a machine of the character described, the combination with a barrel, of a spiral compressor operating therein and having one of 90 its convolutions provided with a slot, a scraper movably mounted to traverse the slotted convolution of the compressor and adapted to be projected rearwardly thereof through said slot, and a spring opposing resistance to the 95 forward movement of the scraper under the action of said slotted convolution, and adapted at the end of such movement to project it rearwardly through said slot, substantially as described. 100

In testimony whereof I have hereunto set my hand in presence of two subscribing witnesses. 105

EDWARD HEMSTRAM.
